UNITED STATES PATENT OFFICE

98,789

DESIGN FOR A MATCH HOLDER

John Russell Wiegand, St. Louis, Mo.

Application December 20, 1935, Serial No. 60,202

Term of patent 7 years

To all whom it may concern:

Be it known that I, John Russell Wiegand, a citizen of the United States and a resident of St. Louis, Missouri, have invented a new, original, and ornamental Design for a Match Holder, of which the following is a specification, reference being had to the accompanying drawing, forming part hereof, in which

Fig. 1 is a plan view of the match holder embodying my new design.

Fig. 2 is a front elevation; and,

Fig. 3 is a side elevation.

I claim:

The ornamental design for a match holder, substantially as shown.

In testimony whereof, I have signed my name to this specification this 18th day of December, 1935.

JOHN RUSSELL WIEGAND.
